UNITED STATES PATENT OFFICE.

ELAM BODMAN, OF GIBBON, NEBRASKA.

WAGON-STEP.

SPECIFICATION forming part of Letters Patent No. 326,098, dated September 15, 1885.

Application filed April 30, 1885. (Model.)

To all whom it may concern:

Be it known that I, ELAM BODMAN, a citizen of the United States, residing at Gibbon, in the county of Buffalo and State of Nebraska, 5 have invented a new and useful Improvement in Common Wagons, of which the following is a specification.

Heretofore common wagons have been made without steps, except a foot board on the side 10 of the bed, much too high for convenience when in use as a family conveyance, as is required of such vehicles in most parts of this great land.

The leading feature of my invention is the 15 folding step, so constructed that when desired it can be folded against the side of the wagon-bed, entirely out of the way. I attain this object by the mechanism illustrated in the accompanying drawing, in which the figure is a 20 perspective view of the step and the attaching-plate.

A represents the horizontal plate. B B represent the projecting end of plate A; C, the supporting-brace; D, the spiral spring; E, 25 the spring-head; F, the horizontal bolt; G, the step; H, the hinge end of step.

The horizontal plate A is fifteen inches long, 30 two inches wide, one inch in thickness at the outer end. It is bolted to the wagon-bed and foot-board at the side with two or more bolts, leaving the outer end projecting one inch. The projecting end B B is of such shape as to form part of the hinge, with the hole through

it for a horizontal bolt, L, one-fourth inch in diameter, with its nut. Below and back of 35 this bolt is a hole drilled one-half inch in diameter, two inches long, to inclose the steel or brass spiral spring D, three eighths inch in diameter, one and a half inch long; also, the spring-head E, of wood, seven-sixteenths 40 of an inch in diameter, one-half inch long, with a shoulder to convey the force of the spring to the hinge to hold the step in place when not required.

The supporting brace C secures the step G 45 in the proper position for use.

The movable part of the step G may be of any desired length and shape, or of the stirrup form shown in the drawing, the top H being so formed that when joined by the bolt F 50 to the plate A at B B it will become a complete and perfect hinge.

I am aware that prior to my invention folding steps have been in use for carriages. To such I lay no claim. They were altogether 55 different from the hinge-step which I have invented as an improvement to wagons.

What I claim, and desire to secure by Letters Patent, is—

The hinge-step, with its supporting-brace 60 and spring, applied to wagons, all substantially as set forth.

ELAM BODMAN.
